UNITED STATES PATENT OFFICE.

BEVILL W. WHITWORTH, OF CEDAR FALLS, IOWA, ASSIGNOR OF ONE-THIRD TO THOMAS A. WHITWORTH AND ONE-THIRD TO CHARLES S. WHITWORTH, BOTH OF CEDAR FALLS, IOWA.

GRAIN-DOOR.

1,319,368.

Specification of Letters Patent.

Patented Oct. 21, 1919.

Application filed December 22, 1917. Serial No. 208,442.

To all whom it may concern:

Be it known that I, BEVILL W. WHITWORTH, a citizen of the United States of America, and a resident of Cedar Falls, 5 Blackhawk county, Iowa, have invented certain new and useful Improvements in Grain-Doors, of which the following is a specification.

My invention relates to improvements in 10 grain doors, particularly those employed on a railway box-car, and the object of my improvement is to furnish a door which will be movable longitudinally along the outer face of a car, and which will be movable 15 to shift into or out of a door-casing to a position for such longitudinal movements, without obstructing the door-opening and without in any way modifying the interior walls of the car. Other improvements will 20 be more specifically described, pointed out in the appended claims, and shown in the drawings, in which Figure 1 is an elevation of a portion of the outside of one side of a box-car equipped with my improved grain 25 door, the latter being shown in its closed position; Fig. 2 is a fragmental view, in plan, of this part of the car and closed door as shown in said Fig. 1, but with parts removed; Fig. 3 is an enlarged fragmentary 30 view of said door and the movable closure for the crevice between one side edge of the door and the casing jamb; Fig. 4 is a like view to that given in said Fig. 1, but showing the door shifted away from the door-casing opening; Fig. 5, like Fig. 2 is a fragmental plan view of the parts shown in Fig. 4, with parts removed or sectioned away; Fig. 6 is a rear elevation of the door and its casing; Fig. 7 is an enlarged detail plan 35 view of the movably-connected fixed and movable rails and the mechanism for releasably holding the movable rail; Fig. 8 is an elevation of parts shown in said Fig. 7, with the lower anti-friction bearing and guide 40 rail, and showing the door after its opening movement has commenced; Fig. 9 is a plan view similar to Fig. 7, but showing the moving parts in an intermediate position, and Fig. 10 is a like view, showing these parts

in their final positions; Fig. 11 is an elevation of the parts shown in Fig. 10, showing the cam completely rotated; Fig. 12 is a transverse vertical section taken on the broken line 12—12 of Fig. 10, and looking in the direction indicated by the arrow. 55

In the drawings, similar numerals of reference denote corresponding parts throughout the several views.

The numeral 1 denotes a railway box-car having a door-casing 2, whose opening may 60 be closed by a door 4, the latter being movably supported as follows.

On the outside of the door-casing, over its opening, is supported a track-rail 22, preferably a Z-bar in cross-section, while on the 65 outside of the car, at the same height, is bracketed a spaced fixed track-rail 23, the rail 22 being bodily translatable to or from the car, so that one of its ends may be brought to abut upon an end of the fixed 70 rail 23, to place the two rails in longitudinal alinement. A fixed bracket 28 on the car, as shown in Fig. 5, has a longitudinal slot 29 to receive a bolt 30 which also passes through an end of the rail 22, the bolt being 75 slidable in said slot, when the rail 22 is shifted outwardly away from the car 1. Another bracket 44 is fixed on said car at the opposite side of the door-casing 2, and has a horizontal part 45 provided with a longitudinal slot 50 through which extends a depending T-head lug 51, shown in Fig. 8, to disconnectably and movably connect the other end of the rail 22, here denuded of 80 part of its lower flange, to said bracket. 85 The adjacent end of the fixed rail 23 is secured to the outer extremity of the bracket 44, and has its end denuded of part of its web and upper vertical flange over said slot. Another bracket 32 supports the other end 90 of the rail 23.

The door 4 has its edges preferably seated and extended into rabbeted grooves 3 in the adjacent parts of the door-casing, to serve as stops and closing-means. The door has 95 a pair of erect hooked bars 24 secured to its upper part on spacing block 70 to serve as hangers, in each of which are alined orifices

to receive the pintles of rollers 25 which roll along the upper flat parts of the rails 22 and 23. As shown in said Fig. 2, when the door is seated or closed within the door-casing 2, the rail 22 is shifted bodily inwardly toward and nearly in contact with the outer face of the car 1, being thus considerably offset from and out of alinement with the fixed rail 23.

- 10 On the outside of the door are handles 5, which may be used to draw the door bodily away from its seat or to shift it longitudinally along said rails.

Referring now to said Figs. 7 to 11 inclusive, the numeral 32 denotes a bracketed shelf fixed on the side of the car 1, said shelf having the longitudinal edge of cam form and having a roller 52 rotatably mounted on a stud 53 thereon to extend 20 slightly beyond its edge. This shelf underlies the horizontal slotted bracket 45, spaced therefrom, and is cut away at the rear sufficiently to seat it above the depending bracket part 44 as also over the depending 25 part of a smaller bracket 46, the horizontal part of the latter resting across the shelf 32, and both orificed in line with the orifice in the overhanging bracket part 45, said alined orifices receiving a short rock-shaft 42 on 30 whose upper end above the bracket 45 is fixedly mounted a cam 33 having a reentrant recess 41 intermediate between a curved part 33' and a flattened part 43, the latter being undercut, as shown in Fig. 11. Between the 35 brackets 45 and 32 and overlying the bracket part 47 of the bracket 46, a bifurcated arm 48 is fixed on the rock-shaft 42 to extend horizontally therefrom and has a roller 49 rotatably mounted between its forks.

- 40 When the door 4 is seated in the rabbets 3 of the casing 2 the extended part 54 of the movable rail 22 extends slightly behind the flattened part 43 of said cam.

When the door 4 and the rail 22 are 45 moved together outwardly, the end 54 of the rail rocks the cam, its shaft 42 and the arm 48, having entered the recess 41 of the cam 33. When the door 4 is shifted longitudinally to the right on the now alined rails 50 22-23, it contacts with and rides upon the roller 49 in said arm 48, thus holding the cam 33 fast against the movable rail 22 at its end part 54 to lock the rails 22-23 in alinement. The rails are thus retained in 55 fixed alinement until the door is shifted back to the left to release said roller 49.

In the operation of translating the door and movable rail outwardly, as above described, the roller 52 bears against the inner 60 face of the door while being moved to the right, as an anti-friction bearing, the cam edge of the shelf 32 also acting as an inclined bearing for the door in its further

progress to the right. A like bracketed shelf 56 fixed on the car below the shelf 32 65 carries a rotatable roller 57, as shown in Fig. 8, which likewise acts as an anti-friction bearing for the lower part of said door while the latter is being translated to the fixed rail 23. A guard-rail 20 is provided 70 at the lower part of the door to overlie it, and is supported on brackets 69 to prevent any movement of the lower end of the door outwardly past that limit.

Bracket-arms 19 are fixed to the car adjacent the upper and lower parts of the left-hand vertical edge of said door, inclined outwardly obliquely as indicated in said Figs. 4 and 5. When the door is shifted back from its fully opened position to its 80 first position, the left-hand vertical edge of the door engages these sloping arms and is pushed inwardly to its seat in the door-casing. While this is being effected, the extended part 54 of the rail 22 rocks the cam 85 33 its edge passing into the recess 41, and the arm 48 rocking to its first position. I have shown in said Figs. 1 and 3, fastening-means and crevice-closures for said door when the door is seated in the door-casing 90 rabbets 3.

The numeral 39 denotes a flat bar, or which may be an angle-bar, positioned vertically alongside the T-iron side-plate 9 of said door and hung on hinges 37 having extensions or hasps 38. On said door in line with said hasps are plates 34 having paired lugs 35 to receive the hasps between them, the lugs being orificed to receive split-keys 36 to fasten the hasps releasably to the lugs, 100 when the bars or angles 39 are swung over to cover the crevices between the door-casings and the T-iron 9, and also overlie the plates 9 to secure the door in place in its seat. The T-irons 9 seal the rabbet-crevice 105 40 between the door edge and the jamb 2. The crevices are thus sealed, and exit of small grain avoided. Certain of these closures 39 may be dispensed with when desired, as indicated in Figs. 4 and 5, and other fastening means employed without departing from the principle of my invention.

A swinging door or grain-outlet 6 is provided in the lower part of the door 4, hinged thereto and operated by means of lever-arms 115 7 on double-joint hinges, to simultaneously lift and swing outwardly said door, but this feature is not claimed herein, being specifically claimed in a pending application for patent.

It will be observed that in my improved device, the grain door is suspended outside of the car, is translatable longitudinally therewith, and that there are no parts extending into the interior of the car to obstruct loading thereof.

It is to be understood that this invention is intended to include all mechanical equivalents of its parts, and that various changes can be effected without departing from its principles.

Having described my invention, what I claim as new, and desire to secure by Letters Patent, is:

1. In combination, a door casing, a door 10 removably fitting said casing, a track-rail mounted above said casing and translatable outwardly, said door being movably supported on said track-rail, a fixed rail in a plane parallel with said door casing and in 15 alinement with said movable rail when the latter is moved outwardly, and mechanism coacting with said door for releasably retaining said movable rail in alinement with the fixed rail when the door is being shifted 20 from one to the other.

2. In combination, a door casing, a door removably fitting said casing, a track-rail mounted movably above said casing, said door being supported for longitudinal movement upon said rail, a fixed rail, and mechanism coengaging movably with both the movable rail and said door for securing the movable rail releasably when the door is shifted from the movable to the fixed rail, 25 said mechanism becoming released from said movable rail when the door is shifted back out of contact therewith, permitting the returning of said movable rail and door to their first positions.

3. In combination, a door casing, a door removably fitted therein, a track-rail movably mounted above said casing, a fixed track-rail, said door having hangers supported on said movable rail for longitudinal movements therealong, mechanism coacting with both said movable rail and said door to first, be changed in position when the rail is shifted outwardly from the casing into alinement with the fixed rail, and second, to releasably hold said movable rail in alinement with the fixed rail when the door is shifted into contact with said mechanism.

4. In combination, a door casing, a door removably fitted therein, a track-rail movably mounted above said casing, a fixed rail, said door being movable longitudinally along said movable rail, mechanisms coacting with said door and said movable rail to hold the movable rail in locked alinement with the fixed rail when the door is shifted longitudinally, and deflecting-means mounted fixedly adjacent said door and engageable thereby when the door is moved back upon the movable rail to deflect the door and said movable rail back to their first positions.

5. In combination, a door casing, a door fitted therein removably, a track-rail mounted movably above said door-casing to be moved

outwardly therefrom, said door being hung on said rail for translation therealong, a fixed 65 rail, said movable rail being movably connected to said fixed rail and movable into alinement with said fixed rail, a cam rocking adjacent to the connected ends of said rails and coengaged by said movable rail, an 70 arm connected to said cam adapted to contact at times with the adjacent part of said door, said cam and arm operating when said alinement is completed to hold the rails in alinement releasably, by contact of the door 75 with said arm.

6. In combination, a door casing, a door removably fitted therein, a track-rail supported above said casing, said door being supported on said rail for longitudinal 80 movements therealong, a fixed rail, a movable connection between abutting ends of said rails, mechanism movable into a position to be contacted by said door to hold the said rails in alinement releasably, when the 85 door is moved longitudinally from the movable to the fixed rail, or reversely.

7. The combination with a railway-car having a door-opening and movable supporting-means thereover, of a door mounted 90 upon the outside of said car for movements thereover, a rotating member mounted on said car adapted to coact with said supporting-means when the door and said supporting-means are moved in certain directions, 95 and a device operated by said rotating member, connected thereto and moving synchronously therewith to engage the door and hold the latter in a desired position.

8. The combination with a railway-car 100 having a door-opening, of a closure for said door-opening operable to close it or to be removed outwardly out of alinement therewith, said door moving on the outside of the car only, and mechanism mounted upon the 105 outside of the car adapted to detachably interlock with said closure to hold the latter detachably in a desired position.

9. The combination with a railway car having a door-opening, of a door for said 110 door-opening having movable hangers and located without the car, supports on said car having relatively movable elements, said door being suspended by said hangers from said supports for translation therewith and therealong, and mechanism mounted on the car for intermittent coaction with said supports and said door to frictionally contact with the door to hold it releasably in a desired position.

10. The combination with a railway-car having a door-opening, of a door located without the car movable to and from the door-opening and also along the car, fixed and movable supporting elements mounted 125 on the outside of the car and movably con-

ected together, the door being movable with the movable element and therefrom on and off the fixed element, and mechanism coacting first with said movable element, and second with said door during the translation of said element outwardly and the movement of the door along said elements longitudinally of the car, to hold the movable element.

in an alined position relative to the fixed elements.

Signed at Lincoln, Nebr., this 8th day of Dec., 1917.
